UNITED STATES PATENT OFFICE.

SILAS M. GOFF, OF EAST ADDISON, VERMONT.

IMPROVEMENT IN CULTIVATORS.

Specification forming part of Letters Patent No. 31,382, dated February 12, 1861.

To all whom it may concern:

Be it known that I, SILAS M. GOFF, of East Addison, in the county of Addison and State of Vermont, have invented a new and Improved Cultivator; and I do hereby declare that the following is a full, clear, and exact description of the same, reference being had to the annexed drawings, making a part of this specification, in which—

Figures 1 and 2 are side sectional views of my invention; Fig. 3, a plan or top view of the same; Fig. 4, a diminished detached view of the rear of the axle.

Similar letters of reference indicate corresponding parts in the several figures.

To enable those skilled in the art to fully understand and construct my invention, I will proceed to describe it.

A A represent two wheels, B, their axle, and C C thills attached thereto.

To the back or rear side of the axle B there are secured a series of loops or staples, a. These staples may extend the whole length of the axle, as shown clearly in Fig. 3, and they may be formed of a metal bar bent or curved in zigzag form, the bar being firmly bolted to the axle.

D represents a frame, which is formed of two parallel side pieces, b b, connected by traverse-bars c, and having a share, E, attached to it. This share is formed of a flat plate connected to side pieces, d, between which and over the plate there is placed a shaft, F, the journals of the latter being in the side pieces. The shaft F is provided with radial spikes or teeth e, and the plate or share E has vertical teeth f attached to its upper surface, between which teeth the teeth e of the shaft F rotate. The shaft F is driven by a belt, g, which passes around a pulley, h, attached to the inner side of one of the wheels A, as shown in Fig. 3.

To the back end of the frame D there is attached a gage-roller, G, said roller being fitted in an adjustable bar, H, by regulating which the depth of share E may be graduated as desired.

The frame D is provided with handles i i, and the frame may be elevated, so that the share E may be raised above the obstructions

when required by means of a lever, I, the front end of which is fitted to the axle B, as shown at j, and the lever connected by a link, k, to the frame, as shown at l in Fig. 1.

To the front end of each side piece b of the frame D there is attached a hook, J, and these hooks are fitted in the proper loops or staples a, which are attached to the axle. The hook J and staples a form the connection between the frame D and the axle B, as shown clearly in Figs. 1 and 3.

K is a frame, in which two oblique shares, L, are placed. Both of these shares are shown in blue in Fig. 3, and also the frame K. The shares L are attached to an adjustable bar, M, and to the back part of the frame K there is attached a swinging or adjustable frame, N, which has a segment-bar, O, attached to it, said bar passing up through a cross-piece, m, of the frame, and secured therein at any desired point by a pin, n. The frame N has a roller, N', in its lower end. By adjusting this bar O in the cross-piece m the frame N may be secured in a more or less inclined position, and the depth of the shares L L regulated as desired.

The front ends of the side pieces of the frame K have hooks P attached, and these hooks are fitted in the staples a when the covering-shares L are used.

From the above description it will be seen that when the frame D is used the share E is designed to work between the rows, as the share is a cultivator and the revolving toothed shaft F is a pulverizer. When, however, the frame K, with its shares L L, is used, the latter are designed to cover the seed, and consequently the frame K requires to be attached to the axle B, so as to have a position relatively therewith somewhat different from the frame D, as the shares L work one at each side of the rows. This will be fully understood by referring to Figs. 3 and 4, the blue circles in the latter figure showing the position of the shares L and the red circle the position of the share E. The attaching, therefore, of the frames D K to the axle B by means of the hooks and staples, as shown, admits of this varying position of the frames,

and consequently the same axle and wheels may be used both for a cultivator and covering device.

Having thus described my invention, what I claim as new, and desire to secure by Letters Patent, is—

The arrangement of the adjustable shares L, bar M, and frame K, with the frame N,

segment-bar O, roller N', frame D, share E, toothed shaft F, and hooks J, in the manner and for the purpose herein shown and described.

SILAS M. GOFF.
